APPARATUS FOR BENDING TUBES OF FIBER AND SIMILAR MATERIAL

Application filed July 28, 1928. Serial No. 286,073.

The invention relates to a method and apparatus for bending tubes constructed of hygroscopic material such as vulcanized fiber, hard paper tubes, or tubes composed of other cellulose material.

In the manufacture of fibrous tubes it is the custom to produce the same by winding upon a mandrel a wet web of fibrous pulp such as cellulose pulp,—the wet web of pulp being formed by a cylinder mold or other web-forming mechanism and being conveyed to the winding mandrel by any suitable form of conveying means. As a result of this operation, there is formed upon the mandrel a tube having a wall which is substantially homogeneous. When the winding operation is completed, the tube itself is moist and it is then ordinarily subjected to a drying operation by which the moisture is removed.

The present invention relates to a method of bending such fibrous tubes after the forming mandrel has been removed. This may be accomplished before the tube is permitted to dry, or if it is dried the tube may be moistened so as to condition it for the bending operation, for it is a pre-requisite that the tube shall be in a condition to bend, and in a moist condition they bend best. A moist paper or fiber tube is easily collapsible since the walls thereof under these conditions possess little strength or resistance.

One of the problems which presents itself in the bending of such tubes is to prevent the malformation of the tube and to maintain the circularity of the tube in cross section. I have solved this problem by causing yielding outward pressure to be exerted against the interior of a moist tube during the bending operation, and then removing the moisture

from the tube while it is still subjected to such pressure. This outward pressure may be provided in a number of ways. For example, the moist tube may be filled with sand or other granular material which will serve to maintain the circularity of the walls during the bending operation and until the bent tube is dried. Or, if desired, gas under pressure may be maintained within the tube during and after the bending operation. Another

means is to insert an expanding helical spring

or coil within the tube, the outward pressure of which is sufficient to prevent deformation of the tube during the bending of the tube and until it is dried and set in the desired bent form.

I have also provided an improved apparatus by means of which a plurality of tubes may be bent at one time, and by means of which a uniform bend may be secured, without marring the walls of the tube.

The invention will be more readily understood by reference to the accompanying drawings, in which:

Fig. 1 is a top plan view of a bending apparatus especially designed for bending gas filled tubes and for heating the gas during the bending and subsequent drying of the tubes in order to maintain the proper degree of pressure within the tubes.

Fig. 2 is a longitudinal sectional view of the apparatus the section being taken through one of the tubes, certain parts being shown in elevation, this view showing the relation of parts when the tubes are in place within the forms, and just before the bending operation.

Fig. 3 is a view similar to Fig. 2 showing the parts of the device when the tubes are being bent.

Fig. 4 is a detail vertical sectional view showing a means for heating the tubes.

Fig. 5 is a detail perspective view showing an extension shield, adapted to be pivotally attached to one of the tube-bending forms.

Fig. 6 is a perspective view of a modified form of tube bending device, particularly designed for bending a plurality of tubes which may be filled with sand or other granular material.

Fig. 7 is a central transverse vertical section through the tube-bending forms, and showing in elevation the means for clamping together the upper and lower members of the apparatus.

Fig. 8 is a view similar to Fig. 7, but taken near one end of the apparatus and showing in elevation the cooperating means for insuring proper registry of the complementary portions of the bending forms.

Fig. 9 is a central longitudinal sectional

view through one of the tube-forming members of the apparatus, a bent tube, filled with sand, being shown in section.

Fig. 10 is a view similar to Fig. 6, but showing a further modification in which coil springs are employed for maintaining the circularity of the fiber tubes.

Fig. 11 is a view similar to Fig. 9, but showing a spring substituted for the granular material employed in Fig. 9.

Fig. 12 is a fragmentary view in elevation showing a detail of the modification disclosed in Figs. 10 and 11.

Referring first to the form of apparatus shown in Figs. 1-5 inclusive, the bending device consists of a bed member 10, and an upper press member 11 pivotally connected to the bed member by means of the hinge 12. The bed member 10 carries the lower halves 13 of a plurality of tube forms, herein shown as three in number, while the upper member 11 carries the upper halves 14 of the tube forms. These forms are of the proper degree of curvature desired in the completed bent fiber tube.

For bending fiber tubes it is necessary to first soak them in water until they become moist and flexible. The tubes 15 are then inserted in the bending matrices as shown in Fig. 2, the lower ends of the tubes are closed air tight by means of gaskets 16 which are held in place by caps 17, which in turn abut against projections 18 on the lower portion of the form. The caps 17 serve to protect the ends of the tube against injury or marring during the bending operation. To each of the lower forms is pivoted an extension or shield 19, the purpose of which is to prevent marring of the tube at that end of the tube form, as would obviously be the case, if no such means were provided. In order to maintain each of the tubes gas tight spring pressed closure members 20, of rubber or like material, are provided at the ends of the tubes opposite the gaskets 16. These closure members are carried by threaded rods 21 extending through a bar 22, which is carried by a lever 23 secured to one of the pivoted shields 19. Springs 24 react between the bar 22 and the closure members 20.

In order to prevent collapsing of the moist fiber tubes heat is applied, which expands the air within the closed tubes and generates steam. To supply the necessary heat gas burners 25 and 26 above and below the tube forms are provided. Sufficient pressure will be generated within the tubes by this heating operation, to prevent collapsing of the tubes as the upper form members are lowered to the position shown in Fig. 3 by means of an operating handle 27 or other operating means, and the form may be secured in this lowered position by means of a latch member 28, provided with a notch 29, which coacts with a pin 30 upon the operating handle 27. As the

tubes are bent the extension shields 19 are rotated about their pivots 31 and prevent marring of the tubes at the ends of the lower tube forms 13. As the shields are rotated the rod 23 carried by the central shield, swings upwardly, carrying with it the bar 22 and the closure members 20, which swing in the same arc as the tubes themselves, and in this manner the gas tight fit is maintained at all times.

After the fiber tubes have been bent they are maintained in the bending forms until they have completely dried, and hardened in the bent form. The drying operation will be assisted by the application of heat from the burners 25 and 26. The pressure is maintained within the tubes until they have hardened sufficiently to prevent collapsing.

Means other than gas pressure for maintaining the circularity of the fiber tubes during the bending operation may be provided. In Figs. 6, 7, 8 and 9, a device is shown in which sand or other granular material is employed for this purpose.

The apparatus is similar to that described in connection with Figs. 1-5 inclusive. In this case, however, the upper member 35 carrying the upper halves 36 of the tube forms, instead of being pivoted to the lower or bed member 37 which carries the lower halves 38 of the tube forms, is provided with grooved guide lugs 39 which coact with posts 40 extending from the bed member and insure the accurate positioning of the two halves 36, 38 of the tube forming members one upon the other. Spring catches 41 are provided for holding the upper and lower members 35, 37 together after the bending operation and while the fiber tubes 42 are drying and hardening.

In operation of the device, the ends of the fiber tubes 42 to be bent, are soaked in the manner previously described and are filled with sand 43, in order to maintain their circularity. They are then placed in the tube bending forms and closed at their lower ends by means of gaskets 44 and caps 45. Extension spades 46 are employed for preventing marring of the tubes, and a bar 47 carried by rods 48 attached to two of the pivoted shields is employed to prevent spilling the sand from the tubes. The tubes, after being bent, are held in the forms until the moisture has dried and the tubes have set and hardened in bent form. The drying operation may be hastened by applying heat, for example, by placing the forms within an oven.

In Figs. 10, 11 and 12, a third modification of the invention is disclosed. The parts of the bending apparatus are the same as shown in Figs. 6-9 inclusive, but in this case the circularity of the fiber tubes 42 is maintained by means of coil springs 50, which exert a constant outward pressure and prevent def-

ormation of the moist tubes during and after the bending operation. These springs, as shown, are in the form of tightly coiled helices pointed at their ends.

5 The last coils of the helices opposite the pointed ends are passed through slots 51 in the bar 47 and then turned at right angles, in order to hold the helices in place. The moist fiber tubes may then be slipped over 10 the helices from the pointed ends upwardly and the caps 45 applied. The upper member of the tube bending apparatus is then applied and pressed into position and clamped until the tubes have dried. When the tubes 15 have sufficiently dried and hardened so as to prevent collapsing, the helical springs may be removed after turning the end coils of the springs in such a direction as to tighten the helices. This tightening of the springs 20 is necessary for the reason that the fiber tubes contract as they are dried and therefore could not be readily separated from the springs unless the helices were contracted.

In all the forms of my invention the mode 25 of operation is substantially the same. When the parts are in the position shown in Fig. 2, the upper or convex form member is tangent to the tube and in contact therewith at a point or on a semi-circular line at the place 30 of contact. The two ends of the part to be bent are supported on the base member of the bending form. As the movable jaw descends, the contact between the tube and upper member is extended toward the ends 35 of the tube, while the contact with the lower member is extended inwardly from both ends toward the center. At first the tendency is to bend the tube at the middle of the portion to be bent, and as the bending proceeds, the 40 curve extends in both directions from the middle. The pressure of the upper member against the tube is transmitted through the material of the tube to the core, and from the core to the lower half of the tube, until 45 finally the entire tube is pressed into the lower member and pressed downwardly against the core by the upper member.

It is apparent, therefore, that the core operates with the upper member to receive 50 and transmit bending stress to the lower portion of the core, until the parts are in the position shown in Fig. 3, when the core operates with both the upper and lower bending members to compress the tube and cause 55 it to conform to the surfaces of both the core and the form members.

The upper portion of the tube is shortened and there is a tendency to produce buckling and unevenness, and on the other hand, there is a tendency to stretch the lower portion of the tube mostly at its middle, making the tube non-circular and uneven in thickness. My invention avoids both of these objections 60 and makes the tube smooth both exteriorally and interiorally, as well as circular inside and

outside. This circularity is a result in part of compression of the thicker parts of the uneven tube and in part it is due to the flow of the plastic material.

Several modifications of the invention have been described for the purpose of illustration, but it is obvious that other forms of apparatus than those herein set forth may be employed for carrying out the herein described method of bending fiber or other plastic tubes.

Where I have claimed the forms as grooved, I do not limit myself to channels cut or molded in the face of a solid block, but the grooves or channels may be formed in any suitable manner, as by bending or corrugating.

What I claim is:—

1. An apparatus for simultaneously bending a plurality of moist fiber tubes into the desired curvature, comprising a pair of relatively movable members carrying a plurality of complementary halves of tube bending forms, said forms having complementary grooves in their working faces to closely engage the outside surfaces of the tubes and also having a curvature conforming to that desired in the bent tubes, and means for operating within the tubes to prevent collapse and maintain the circularity of said tubes during the bending operation.

2. An apparatus for simultaneously bending a moist fiber tube into the desired curvature, comprising a pair of relatively movable members carrying complementary halves of a tube bending form, said halves having complementary grooves in their working faces to closely engage the outside surface of the tube and also having a curvature conforming to that desired in the bent tube, means for securing together said movable members in such relation that the complementary halves of the tube bending form register with each other, and means for operating within the tube to prevent collapse and maintain the circularity of said tube during the bending operation.

3. An apparatus for bending a moist fiber tube into the desired curvature, comprising a pair of relatively movable members carrying complementary halves of a tube bending form, between which one end portion of the tube is placed, said form having a curvature conforming to that desired in the bent tube, and an extension member pivoted at the end of one of the halves of the bending form, said extension member having means for securing it to the projecting portion of the tube to move therewith, and said extension being adapted to engage the tube during the bending operation for preventing marring.

4. An apparatus for simultaneously bending a plurality of tubes into the desired curvature, comprising a pair of relatively movable members carrying a plurality of

complementary halves of tube bending forms, said forms having a curvature conforming to that desired in the bent tubes, extension members pivoted at the ends of the one set of halves of the bending forms, and adapted to engage the tubes during the bending operation for preventing marring, rods carried by said pivoted extension members, and caps for the ends of the tubes carried by the said rods.

5. An apparatus for bending a moist fiber tube, comprising a pair of relatively movable members carrying complementary portions of the bending form, said form having a curvature conforming to that desired in the bent tube, and means partly within and partly without the tube for maintaining the circularity of said tube during the bending operation.

20 6. An apparatus for bending a moist fiber tube, comprising a movable and a fixed member, each member carrying a complementary portion of a bending form; and an extension shield, conforming in shape to that of the tube to be bent, pivoted intermediate its ends to the fixed member and adapted to prevent marring of the tube at the end of the fixed form.

7. An apparatus for bending tubes comprising a movable and a fixed member, each member carrying a complementary portion of a bending form; an extension shield pivoted to the fixed member and adapted to prevent marring of the tube at the end of the fixed form and a cover for one end of a tube being bent, said cover being adapted to swing about the same pivot as the extension shield.

8. An apparatus for bending fiber tubes comprising a movable and a fixed member, each member carrying a complementary portion of a bending form, each portion being grooved to closely fit the outside surface of the tube, and means for closing the ends of the tubes air-tight during the bending operation.

45 9. An apparatus for bending moist fiber tubes comprising a movable and a fixed form member, each member carrying a complementary portion of a bending form, said portions being grooved to closely fit the outside surface of the tube, and means for acting within the tube to cooperate with the form members for maintaining circularity of the tubes during the bending operation.

55 10. An apparatus for bending moist fiber tubes into the desired curvature, comprising a pair of relatively movable form members, carrying complementary halves of a tube bending form, said form having a curvature conforming to that desired in the bent tubes, said halves being grooved to closely fit the outside of the tubes, and means for closing the ends of the tubes during the bending operation.

65 11. An apparatus for bending moist fiber

tubes into the desired curvature, comprising a pair of relatively movable form members, carrying a plurality of complementary halves of tube bending forms, said forms being grooved to fit the outside surfaces of the tubes and having a curvature conforming to that desired in the bent tubes, means within the tubes cooperating with the form members for maintaining circularity of the tubes during the bending operation, and means for closing the ends of the tubes during the bending operation.

12. An apparatus for simultaneously bending a plurality of tubes into the desired curvature, comprising a plurality of relatively movable members carrying a plurality of complementary halves of tube bending forms, rods pivoted adjacent the ends of one set of halves of the bending forms, and covers for the ends of the tubes carried by said rods.

20 13. An apparatus for bending a fiber tube comprising a pair of relatively movable members carrying complementary halves of tube bending forms, pivoted means carried by one of said members, and tube closing means carried by said pivoted means.

14. An apparatus for bending tubes comprising a pair of relatively movable members carrying complementary portion of tube bending forms and means for securing together said movable members in such relation that the complementary halves of the tube bending forms register with each other, said means comprising a plurality of posts carried by one member, and cooperating with a plurality of grooved lugs carried by the other member, and pivoted spring latch members carried by one member and engaging over the other member.

25 15. An apparatus for simultaneously bending a plurality of tubes into the desired curvature, comprising a bed member and an upper member pivoted thereto, said members carrying a plurality of complementary halves of tube bending forms, and means for heating the tubes in said forms comprising upper and lower sets of gas burners, the upper set being movable with said pivoted member, the number of burners in each set corresponding to the number of tube bending forms.

16. An apparatus for bending fiber tubes comprising upper and lower form members movable with reference to each other, a tube closure member having pivoted connection to one of said members, and expansion means carried by said closure member, and cooperating with the said forms during the bending operation, for maintaining circularity of the tube.

17. An apparatus for simultaneously bending a plurality of tubes into the desired curvature, comprising a pair of relatively movable members carrying a plurality of complementary halves of tube bending forms,

having a curvature conforming to that desired in the bent tubes, closure means for said tubes pivotally connected to one of said members, a plurality of coil springs carried by said closure means, and cooperating with said form members to maintain the circularity of said tubes during the bending operation, and means extending through said closure for varying the tension of said springs.

18. An apparatus for bending a tube into the desired curvature, comprising a pair of relatively movable members carrying complementary halves of a tube bending form, said form having a curvature conforming to that desired in the bent tube, an extension member pivoted at the end of one of the halves of the bending form, and adapted to engage the tube during the bending operation for preventing marring, a rod carried by said pivoted extension member, and a cap for the end of the tube carried by the said rod.

19. An apparatus for bending a tube into the desired curvature, comprising a plurality of relatively movable members carrying complementary halves of a tube bending form, a rod pivoted adjacent the end of one of the halves of the bending form, and a cover for the end of the tube carried by said rod.

20. An apparatus for bending tubes comprising a pair of relatively movable members carrying complementary portions of a tube bending form and means for securing together said movable members in such relation that the complementary halves of the tube bending form register with each other, said means comprising a plurality of posts carried by one member, and cooperating with a plurality of grooved lugs carried by the other member, and pivoted spring latch members carried by one member and engaging over the other member.

21. An apparatus for bending a tube into the desired curvature, comprising a bed member and an upper member pivoted thereto, said members carrying complementary halves of a tube bending form, and means for heating the tube in said form comprising upper and lower gas burners, the upper burner being movable with said pivoted member.

22. An apparatus for bending tubes into the desired curvature, comprising a pair of relatively movable members carrying complementary halves of a tube bending form, having a curvature conforming to that desired in the bent tubes, closure means for said tube pivotally connected to one of said members, a spring carried by said closure means, and cooperating with said form members to maintain the circularity of said tube during the bending operation, and means extending through said closure for varying the tension of said spring.

23. Apparatus for bending moist fiber tubes comprising means for causing a resistance to collapse or inward radial movement

of the tube in any direction, and means closely surrounding the tube and opposing outward radial movement to insure circularity of the tube when bent.

24. Apparatus for bending moist fiber tubes comprising means for causing a resistance to collapse or inward radial movement of the tube in any direction, means closely surrounding the tube and opposing outward radial movement to insure circularity of the tube when bent, and means for heating said tube while it is held by the apparatus.

25. A device for bending tubes composed of moist fibrous material, comprising a movable and a fixed member, each member carrying a complementary portion of a bending form, an extension shield pivoted to and overlapping the fixed member and adapted to prevent marring of the plastic tube during the bending operation, and granular means within the tube for preventing collapsing of the tube while moist.

In testimony whereof I affix my signature.

DANIEL B. REPLOGLE.
